CLAIM

The ornamental design for a straight dual raceway fitting, as shown and described.

DESCRIPTION

FIG. 1 is a perspective view of a straight dual raceway fitting showing our new design;

FIG. 2 is an end view of thereof, the opposite end view being identical;

FIG. 3 is a side view of thereof, the opposite side view being identical;

FIG. 4 is a top view thereof;

FIG. 5 is an exploded view thereof;

FIG. 6 is a fragmentary detail end view of the ornamental grooved portion of the right sidewall of the raceway fitting, the corresponding portion of left sidewall being a mirror image; and,

FIG. 7 is a fragmentary detail end view of the ornamental, central grooved portion of the raceway top wall.
